CARL O. HEDSTROM, OF PORTLAND, CONNECTICUT.

MOTOR-CYCLE FRAME.

1,111,152.

Specification of Letters Patent.

Patented Sept. 22, 1914.

Application filed March 7, 1914. Serial No. 823,139.

To all whom it may concern:

Be it known that I, CARL O. HEDSTROM, residing in Portland, county of Middlesex, and State of Connecticut, have invented certain new and useful Improvements in Motor-Cycle Frames, of which the following is the specification.

This invention relates to improvements in motorcycle frames; and an object is to provide a construction in which the rear wheel is permitted to have free and unrestricted vertical movements.

Heretofore, in motorcycle construction it has been the common practice to form the rear portion of the supporting springs, which are interposed between the rear axle and the frame with short curves or bends therein. This practice has been found objectionable on account of the large percentage of the breakages of the springs which occur, and it has also been found objectionable because the springs did not yield or bend over their entire length when in use.

In the present invention it is contemplated to use plate springs located between the rear axle and the framework. These springs are pivotally attached at their center portions to a portion of the main frame which extends rearwardly from the saddle post, whereby the springs may turn about this point of attachment and utilize the full length of the springs for cushioning effect. In practice it has been found necessary to pivotally attach the forward ends of the springs to the frame work by means of pivoted links. Such a construction permits the entire length of the springs to be used, as will be fully described, and whereby the opposite ends of the springs will be flexed or bent in opposite directions.

The single figure, in perspective, shows the improvement, and in dotted lines the position the parts assume when the rear wheel passes over an elevation in the roadway.

Referring to the drawings in detail: 1 designates the main frame work of the machine, 2 a rigid post extending upwardly from the crank-hanger construction to the yoke block 3 with which it is integrally formed.

4 designates the usual members which extend rearwardly from the crank-hanger and to which they are pivotally connected to the main frame as indicated at 5. 6 are posts that are pivotally connected to the

rear axle forks 7, at the points 8. The upper ends of these posts are pivotally attached to the lower leaves 9 of the plate springs 10, as shown at 10¹. The forward ends of these springs are pivotally attached to the post 1 by means of the oppositely disposed links 11 at the points 12, the upper ends of the links 11 being pivotally attached to the main frame 1 at 13. Mounted on the springs 10, near their middle portions are pivot blocks 14. These blocks are rigidly secured to the plate springs 10 by means of the clamps 15¹. Pivotally attached to the blocks 14 is the rigid yoke member 3 as indicated at the points 15. This yoke member extends forward as indicated at 16 and is formed with a boss or projection 17 on which rests and is secured the saddle of the vehicle in the usual manner. The usual upper and lower brace bars of the vehicle are shown at 17¹ and 17².

Referring now to the operation of the machine, it will be seen that the frame and plate springs 10, should the vehicle pass over an elevation in the roadway, will assume the dotted line positions shown. The rear axle which is connected to the forks 7 would be thrown upward, carrying the rear ends of the springs 10 in this direction which would cause the springs to turn about the fixed pivot points 15. The links 11 would assume the dotted line position 11¹ by turning upon their pivots 13. By means of this construction the full length of the plate springs 10 would be brought into use, and, as there are no sharp turns or bends in these springs they would not be so liable to break as those in common use in which a short loop is formed at the ends through which the usual pivot pins pass, the break, as well known, occurring at these short loops.

The parts 1, 16 and 3 are rigidly connected together. The parts 4, 6, springs 10, and the links 11 constitute a movable frame work by means of which the rear wheel can move freely in a vertical plane. The springs 10 will automatically move either upward or downward about the fixed pivot points 15 according to whether the wheels fall into a depression, or pass over an elevation in the roadway. Should the rear wheel, indicated in dotted line, drop into a depression, the springs 10 would be flexed or bent in the opposite direction to that shown, the rear ends of the spring would then move downward and the for-

ward ends would move slightly upward by reason of the link connections 11. The links 11 must be provided in order to compensate for the forward movements of the springs which necessarily move through an arc of a circle. When the rear axle of the vehicle drops into a depression, carrying the rear end of the springs 10 downward, and moving the forward ends of the spring upward, 10 the links 11 will then move a very slight amount, because the forces on the links 11 are then very nearly in the line connecting the pivots 12 and 13, but when the spring is bent or flexed into the position shown in 15 the figure the forward end of the springs 10 will move through an arc which will draw the links 11 forward into the dotted line position 11¹.

What I claim is:

- 20 1. In a motorcycle construction, the combination with the main frame thereof, and a rearwardly extending fork pivotally attached to the main frame, of a spring pivotally attached at its forward end to the main frame, means to attach the rear end of the spring to the rearwardly extending fork of the vehicle, a block rigidly secured to the center portion of the spring, a yoke-member forming a part of the main frame 25 and pivotally attached to said block, whereby when the vehicle passes through a depression or over an elevation in the roadway, the spring will rotate about the yoke-member and the opposite ends of the spring 30 will be flexed in opposite directions, as described.
- 35 2. In a motorcycle, the combination with the main frame, of a fork pivotally attached thereto and extending rearwardly thereof, posts secured to the rear end of said fork and extending upwardly, links pivotally attached to the main frame, springs secured to the links and posts respectively, a portion of the frame being pivotally attached to the center portions of the springs, whereby when the vehicle is in use, the full length of the springs will 40 be flexed, and the opposite ends of said springs will be moved in opposite directions, as described.
- 50 3. A motorcycle frame comprising in combination, a fork pivotally connected to the

frame, a post device secured to the rear end of the fork, a movable link member secured to the said frame, a spring member attached 55 at its opposite ends to said post device and said movable link member respectively, and a pivotal connection between the center portion of the spring and the frame.

4. The combination with the main frame 60 of a machine of the class described, a rearwardly extending fork pivotally connected to the main frame, and of a spring, a link pivotally attached to the main frame, a post secured to said fork, said spring being 65 attached to the post and link respectively, and means for pivotally securing the center portion of the spring to the main frame, whereby the full length of the spring will 70 be flexed when vertical movements are imparted to the pivotally connected rear fork, as described.

5. The combination with the framework of a motorcycle or similar machine, having a rearwardly extending yoke portion 75 forming a part of the framework, a rear fork, pivotally connected to the framework in which the rear axle of the vehicle is mounted, a spring pivotally connected at its opposite ends to the framework and rear 80 fork respectively, and means to pivotally connect the center portion of the spring with said yoke, as described.

6. The combination with the framework of a motor-vehicle, a rear fork pivoted to 85 the framework, a link connected to the framework, a post pivoted to said fork, a spring pivotally connected at one end with the link and at the other with the post, and means to pivotally secure the center portion of the spring to the framework.

7. A motorcycle frame, a plate spring, a link pivoted to the frame, a rear fork pivotally attached to the frame, a post pivotally attached to the rear fork, said spring 95 having a pivotal connection with the link and post, and means to pivotally attach the center portion of the spring to the said frame.
